UNITED STATES PATENT OFFICE

ERSKINE E. BOYCE, OF GASTONIA, NORTH CAROLINA

SEWING MACHINE

Application filed September 4, 1930. Serial No. 479,735.

This invention is an improvement in sewing machines, and more particularly in tufting attachments for such machines.

One of the objects of the present invention is to materially simplify the mechanism and ease the operation of the parts forming the attachment for automatically producing a series of loops, in regular sequence, in sheeting or fabric, and to sever the loops, to 10 form a long pile.

A further object is the provision of comparatively simple and effective means for tufting sheeting or woven fabrics, to produce spreads, rugs and other articles, solely 15 by mechanism.

In the drawings forming a part thereof: Figure 1 is a side elevation, partly in section, of the head of a sewing machine.

Figure 2 is a section on the line 2—2 of 20 Figure 1.

Figures 3 and 4 are views of the lower part of Figure 1 showing the parts in other positions.

The present embodiment of the invention, 25 is shown in connection with the head 1 of a sewing machine, having the usual needle-bar 2, needle 3, and presser foot 4. The needle has the usual eye through which passes the thread 5, which is thrust through the 30 sheet.

The feed dog 6 is connected to a substantially Z-shaped link 7, one end of which is pivoted at 8 to an arm 9, on a shaft 10, and the other end of the link is pivotally connected to a strap 11' carried on a shaft 11 by an eccentric arranged below the feed dog and presser foot. Shaft 11 is rocked by a connection, not shown, from the usual wheel crank, not shown, at the opposite end of the 40 machine, and the eccentric affixed to the shaft and which engages the strap 11' raises and lowers the feed dog 6 at the proper time. Shaft 10 is operated by mechanism, not shown, to give the feed dog its back and forth movement. The eccentric on the shaft 11 is timed in such a way as to raise the feed dog 6 at the forward end of the stroke imparted by shaft 10 and to lower the feed dog 45 at the backward end of the stroke, thus accomplishing the feeding motion.

The feed dog is connected to the link as indicated at 12, and the shaft 11 carries a sickle shaped hook 13, which is adapted to pass through the loop of thread carried downwardly by the needle, as indicated in 55 Figure 1. A blade 14 is pivoted to the shank of the hook as indicated at 15, and a spring plate 16 is arranged on the pivot 15, the spring acting to press the blade toward the hook.

When the shaft 11 is oscillated the feed dog is operated as previously explained, and the hook is oscillated. At the moment when the needle is at the limit of its downward stroke and starts to move upward, a somewhat open loop is formed in the thread, and at this time the bill of the hook 13 enters the loop. When the needle moves upward, the hook holds the loop, and passes through the loop, as far as the offset or shoulder 18 which 60 is formed between the bill portion and the shank of the hook. This shoulder retains the loop while it is being cut by the blade 14.

It will be noticed referring to Figures 1 and 4, that the blade has a tail 20 extending 75 on the opposite side of the pivot 15 from the blade, and this tail is adapted to engage a flattened abutment 21, on the underside of the feed dog, when the parts attain the position of Figure 4. This swings the blade 80 which is the movable part of a shear, the fixed part being constituted by that portion 22 of the hook shank between the pivotal connection 15 and the shoulder 18. The cutting position is shown in Figure 4. Figure 3 85 shows the beginning of the movement of the hook, and Figure 4 the extreme position of the hook through the loop.

The operation is as follows:

Every time the needle descends, the shaft 90 11 is oscillated to cause the bill of the hook to engage within the loop and hold it from retraction with the needle. When the loop passes to the shoulder 18, the movable blade of the shear operates to cut the loop. The 95 movable shear blade is opened by engagement with a fixed abutment 23, connected to the table, the free end thereof being so positioned that the tail 20 strikes the said end when the hook 13 is at the limit of its move- 100

ment to the left in Figure 1. The shear blade is moved in one direction, to cut, by the abutment 21, and in the opposite direction to open by the abutment 23.

5. What is claimed as new is:—

1. In a sewing machine of the class described, having a needlebar carrying a needle, a feed dog for advancing the fabric, and means for guiding the thread to the needle, a shaft mounted below the dog for oscillating movement, a sickle shaped hook secured to the shaft and adapted to pass through a loop carried downward by the needle, and a blade pivoted to the shank of the hook, said 10 blade having a tail, and the feed dog an abutment for engagement by the tail to operate the blade when the hook is at the limit of its forward movement.
2. In a sewing machine of the class described, having a needlebar carrying a needle, a feed dog for advancing the fabric, and means for guiding the thread to the needle, a shaft mounted below the dog for oscillating movement, a sickle shaped hook secured 15 to the shaft and adapted to pass through a loop carried downward by the needle, and a blade pivoted to the shank of the hook, said blade having a tail, and the feed dog an abutment for engagement by the tail to 20 operate the blade when the hook is at the limit of its forward movement, said hook carrying a cutting blade cooperating with the first named blade.

3. In a sewing machine of the class described, having a needlebar carrying a needle, a feed dog for advancing the fabric, and means for guiding the thread to the needle, a shaft pivoted below the dog, a sickle shaped hook secured to the shaft and adapted to 25 pass through a loop carried downward by the needle, and a blade pivoted to the shank of the hook, said blade having a tail, and the feed dog an abutment for engagement by the tail to operate the blade when the hook is at 30 the limit of its forward movement, said hook carrying a cutting blade cooperating with the first named blade, said hook having a shoulder between the cutting blade and the bill of the hook to enable the hook to draw 35 the loop rearwardly on its rearward movement.

4. In a sewing machine of the class described, an oscillating loop engaging hook of sickle shape, including a shank and a bill, and 40 having a shoulder between the shank and the bill, facing away from the bill and on the concave edge of the hook, a blade pivoted to the shank and provided with a tail, and an abutment for engagement by the tail to 45 operate the blade, the hook shank having a fixed blade in rear of the shoulder cooperating with the movable blade.

5. In a sewing machine of the class described including a movable feed dog, an 55 oscillating loop engaging hook of sickle

shape, including a shank and a bill, and having a shoulder between the shank and the bill, facing away from the bill and on the concave edge of the hook, a blade pivoted to the shank and provided with a tail, an abutment on 70 the feed dog for engagement by the tail to operate the blade, the hook shank having a fixed blade in rear of the shoulder cooperating with the movable blade, an oscillating shaft to which the hook is connected, and means for oscillating the shaft. 75

6. In a sewing machine of the class described, an oscillating loop engaging hook of substantially sickle shape and including a shank and a bill, said hook having a shoulder 80 on the concave edge between the bill and the shank and facing the shank over which a loop may engage to prevent withdrawal from the hook, and means to shear the loop.

7. In a sewing machine of the class described, an oscillating loop engaging hook of substantially sickle shape and including a shank and a bill, said hook having a shoulder 85 on the concave edge between the bill and the shank and facing the shank over which a loop may engage to prevent withdrawal from the hook, a movable blade pivoted to the shank and extending to the shoulder, said blade having a tail for engagement by a moving part to operate the blade, and the 90 shank having a cutting edge to cooperate therewith.

8. In a sewing machine of the class described, an oscillating loop engaging hook including a shank and a bill, a movable blade 100 pivoted to the shank and cooperating with the hook as a fixed or ledger blade, the movable blade having a tail, and abutments for engagement by the tail during oscillation of the hook to open and close the blade. 105

Signed at Gastonia in the county of Gaston and State of North Carolina this 2nd day of Sept. A. D. 1930.
